(57) **CLAIM**

The ornamental design for a terminal device, as shown and described.

DESCRIPTION

FIG. 1 is front perspective view of a terminal device showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken line showing of portions of the terminal device is for the purpose of illustrating environmental structure and forms no part of the claimed design. The oblique line shading shown in FIGS. 1-2 represents a glass surface.
